ATTORNEY

UNITED STATES PATENT OFFICE

LOUIS H. WELLENSIEK, OF HOUSTON, TEXAS, ASSIGNOR TO HUGHES TOOL COMPANY, OF
HOUSTON, TEXAS, A CORPORATION OF TEXAS

ROLLER CORE BIT

Application filed March 24, 1931. Serial No. 524,790.

My invention relates to core drills employed in drilling deep wells for oil, gas, water, and the like. It relates particularly to hard formation core drills employing rolling cutters thereon.

It is an object of the invention to provide a construction for the head of the core drill whereby the cutters may be mounted in an advantageous position to cut the bottom of the hole when said cutters are of comparatively small diameter.

It is a further object to provide a mounting for the individual cutters, which will enable the cutters to be supported thereon with the cutter shafts formed integrally with the support.

I also have as an object to provide a cutter head which may be mounted upon the drill collar or support without the necessity of a threaded connection therewith.

It is a further object to provide an effective construction whereby the flushing fluid may be conducted directly upon the cutters.

The invention resides particularly in the manner in which the drill cutters are mounted and assembled upon the head in a substantial but economical manner, whereby a strong and sturdy construction of drill may be obtained at an economical cost.

In the drawing herewith Fig. 1 is a central longitudinal section through a core drill embodying my invention taken on the plane 1-1 of Fig. 4.

Fig. 2 is a perspective view showing the manner of mounting the cutters upon the head of the drill.

Fig. 3 is a perspective view of one of the cutter supports disconnected from the head.

Fig. 4 is a transverse section on a plane 4-4 of Fig. 1.

Fig. 5 is a perspective view of one of the blocks employed in spacing the cutters upon the head and supporting the same in position.

Fig. 6 is a perspective view of one of the locking keys, by means of which the head is held in position upon the head of the drill body.

In the construction of my device, the body of the drill is shown at 5 in Fig. 1 as being of tubular construction, the lower end 6 of

which is increased slightly in outer diameter to engage with the upper ends 7 of the cutter supports 9. The lower end of the body 6 is squared off to engage the upper ends of the cutter supports and to form a close engagement therewith.

The lower end of the drill body has therein a plurality of recesses spaced apart to receive the tubular pins 11 which are screwed therein. A water channel 12 in the drill body extending downwardly in an inclined direction is adapted to connect with the channel 13 through these pins. As will be seen from Fig. 4, there are six of these pins 11 arranged in sets of two and spaced apart by blocks 14, 65 the shape of which is shown best in Fig. 5.

The cutter supports 9 are of the construction best indicated in Fig. 3. There is an upper rectangular block on each support having a longitudinal opening 15 therein to receive the lower end of the tubular pin 11. The inner side 16 is curved to conform to an inner curvature of the drill body. On the lower side of each block is a shoulder 17 formed to fit over and be supported upon the 75 drill head 18. This will be understood from Fig. 2.

Below the shoulder 17, the outer side of each block is extended downwardly and formed into a cutter shaft 19 which is inclined toward the center of the drill and tapered as shown in Fig. 3 to form a bearing for a roller cutter 20. The end of each shaft is formed with a cylindrical portion 21, which may be welded to the cutter head 18 as 80 is shown at 22 in Fig. 1. It is to be understood that each alternate cutter has a shaft inclined at a different angle from that of the adjacent cutter. One shaft may be inclined downwardly and inwardly as shown at 23 85 in Fig. 1, while the adjacent shaft may be inclined upwardly and inwardly as indicated upon the cutter at right of Fig. 1.

The cutter head 18 with the cutter supports 9 mounted thereon and welded thereto by 90 bonds of welding material 24 are secured to the cutter body by means of keys 25 such as are shown in Fig. 6. To receive these keys, the outer side of each of the cutter supports 9 are provided with a mortised recess 26, the 100

inner portion of which is shaped to receive the keys 25. Also, each of the pins 11 secured in the drill body is recessed on its outer side at 27 to receive said keys 25. When the head

- 5 with the cutters thereon as shown in Fig. 2 is inserted upwardly against the drill body, the openings 15 in the cutter supports telescope over the tubular pins 11, bringing the recess 27 on the tubular pins into registration 10 with the slotted recess 26 in the cutter supports. The keys 25 may then be forced into said openings or recesses as indicated in Fig. 4, and the ends bent over to hold the keys in position. These keys are tapered from one 15 end to the other as will be understood from Fig. 6, so that when they are forced into position they will move the head 18 firmly into contact with the lower end of the cutter body.

As will be understood from Fig. 2, when 20 the cutter head is thus attached to the drill body, there will be spaces indicated at 29 in Fig. 2 between the upper ends of the cutter supports and the lower end of the cutter body. This space I contemplate filling with 25 blocks shown at 30 in Fig. 1 which are seated partially in the space between the cutter supports and partially in a recess 31 in the lower end of the cutter body. Upon this block may be mounted a core catcher having cutter dogs 30 37 thereon, such structure, however, forming no part of the present invention.

In the drawing as seen in Fig. 1, the cutter body 5 is shown as having a core barrel 32 fitted within the lower end thereof, leaving a 35 space 33, through which flushing fluid may find its way to the upper end of water channels 12. Outside of the body is a collar 34 separated from the cutter body by a floating sleeve 35 having packing rings 36 thereon on 40 opposite sides to form a fluid tight engagement between the collar and the cutter body.

It is to be understood, however, that the construction of my cutter head may be varied in various ways, and that the use of a packing 45 ring such as is shown at 35 shows no essential part of the present invention. The purpose of the said invention is to form a seal between the collar 34 and the cutter body 5.

The advantages of this construction lie in 50 the fact that the cutters may be secured and assembled in position on the drill without difficulty, and that a strong construction is thus obtained. The cutter pins or shafts 19 are formed integrally with the supports 9 and 55 will thus better resist any tendency to be broken off from the supports. When the cutters are assembled upon the cutter body 18 as shown in Fig. 2, the inner ends may, if desired, be welded to the head 18 as shown in 60 Fig. 1. By forming a connection between the cutter head and the cutter body through the use of tubular pins or shafts as described, I am enabled to avoid the necessity of a threaded connection between the head and the cutter body. This allows a more sturdy con-

struction and allows the core barrel to be attached at a point closer to the cutters and to provide a core catcher close to the bottom of the hole.

It will be seen that the drill may be quickly mounted in position upon the head of the drill and also easily removed by driving the keys 25 from their position and slipping the head off from the ends of the pins 11. The further advantages of this construction will 75 be apparent.

What I claim as new is:

1. A core drill including a tubular body, a drill head, cutter supports on said drill head adapted to abut the lower end of said body, pins on said body adapted to telescope within openings in said cutter supports, means to secure said pins to said supports, whereby said head and body are connected together, and cutters on said supports. 80

2. A core drill including a tubular body, a drill head, cutter supports on said drill head adapted to abut the lower end of said body, pins on said body adapted to telescope within openings in said cutter supports, said pins being tubular and adapted to convey flushing fluid, means to secure said pins to said supports, whereby said head and body are connected together, and cutters on said supports. 90

3. A core drill including a tubular body, a drill head, cutter supports on said drill head adapted to abut the lower end of said body, pins on said body adapted to telescope within openings in said cutter supports, means to secure said pins to said supports including keys inserted transversely of said pins and said supports, whereby said head and body are connected together, and cutters on said supports. 100

4. In a core drill, a body, a drill head, cutters mounted on said head, upwardly extending blocks thereon, removable downwardly projecting pins on said body engaging in said blocks, and transverse keys in said head engaging said pins to retain said head on said body. 110

5. A core drill body, a head connected therewith, cutter supports including blocks mounted rigidly on said head, cutters on said supports, and means on said body engaging said blocks to secure said head to said body. 115

6. A core drill head including a ring shaped member, a plurality of pairs of cutter blocks fitting against and adapted to be welded to said ring, each of said blocks having an inclined cutter shaft integral therewith, and cutters mounted on said shafts. 120

7. In a core drill, a tubular body, a ring shaped head, cutter supports fixed to said head, said supports having recesses therein, pins projecting downwardly from said body and adapted to fit within said recesses, means to secure said pins to said supports and cutters on said supports. 125

8. In a core drill, a tubular body, a ring shaped head, cutter supports fixed to said head, said supports having recesses therein, pins projecting downwardly from said body and adapted to fit within said recesses, means to secure said pins to said supports and cutters on said supports, said pins being tubular and adapted to conduct flushing fluid to said cutters.
- 10 9. A core drill including a tubular body, a ring shaped head, cutter supports welded in position on said head, cutters on said supports, pins detachably connected with said body and adapted to project into recesses in
15 said supports, and means to latch said pins in said head.

In testimony whereof, I hereunto affix my signature, this the 2 day of March A. D., 1931.

LOUIS H. WELLENSIEK.
